DEVICE FOR OBTAINING SOLAR
OBSERVATIONS

Claude H. Wall, Columbus, Ohio

Application May 8, 1939, Serial No. 272,346

8 Claims. (Cl. 33—61)

My invention relates to a device for obtaining solar observations. It has to do, more particularly, with a device for use in conjunction with an engineer's or surveyor's transit or theodolite 5 to make solar observations in order to find the direction of a line; usually referred to as meridian, azimuth, or bearing.

Solar observations are used at the present time by engineers and surveyors in determining 10 the azimuth of a given line. However, at the present time these observations are employed only where great accuracy is not required. For accurate work, engineers and surveyors in making surveys prefer to make observations on 15 Polaris. Although great accuracy can be obtained in this manner, Polaris observations must be made at night and require special arrangements for illuminating the field of view and the mark.

20 As is well known to surveyors and engineers, the azimuth of any line in a survey may be determined by measuring the horizontal angle between the line itself and the direction of the sun's center, as well as the altitude of the sun, and then solving the spherical triangle, pole- 25 zenith-sun, for the spherical angle at the zenith. This computed angle is combined with the measured horizontal angle to obtain the azimuth of the survey line.

30 Solar observations, as indicated, are used at the present time to obtain the direction of a line. However, these observations are not accurate and cannot be performed very quickly. Also, with the present solar observation methods, 35 it is not possible to accurately measure the speed of the sun, both horizontally and vertically, in a quick and efficient manner.

The solar observation methods commonly employed at the present time consist of the quadrant-tangent method and the center-tangent method. With both of these methods, the vertical and horizontal cross-hairs of the transit are 40 employed. These observations are taken either by looking directly at the sun with a transit equipped with a darkener attached to the eyepiece or by using a screen spaced a few inches back of the eyepiece upon which the image of the sun together with the shadow of the cross-hairs will focus when the transit is pointed at the sun. With the quadrant-tangent method, the 45 observations are made by adjusting the telescope of the transit until the edges of the image are tangent with the vertical and horizontal hair lines in either quadrant formed thereby. With 50 the center-tangent method, the observations are

made by adjusting the telescope of the transit until the edge of the image is tangent with one of the hair lines and the center of the image is on the other line. With both of these methods, it is extremely difficult to obtain any high degree 5 of accuracy. In the quadrant-tangent method it is necessary to simultaneously watch two points of tangency 90 degrees apart. In the center-tangent method, one point of tangency must be watched and the center of the image must 10 be located accurately on one of the hair-lines. The reading of the angle on the instrument must be taken when the sun's image is located exactly as indicated above. It is very difficult to get the image of the sun located accurately in the manner indicated and considerable time must be consumed in doing this. Furthermore, with these 15 methods in order to determine the speed of the sun with any degree of accuracy, it is necessary to permit the sun to travel through a distance 20 equal to its full diameter which consumes a considerable period of time.

One of the objects of my invention is to provide a device for obtaining solar observations, in order to find the azimuth of a line, in a highly 25 accurate and quick manner.

Another object of my invention is to provide a device for obtaining solar observations which may be used in taking solar observations in a manner greatly simplified as compared to the 30 ordinary methods of making solar observations.

Another object of my invention is to provide a device of such a nature that the observations may be made in such a manner that pointings 35 can be taken directly and accurately on the center of the sun.

Another object of my invention is to provide a device of the type indicated which is of such a nature that the speed of the sun both horizontally and vertically may be accurately determined. 40

Another object of my invention is to provide a device for use in obtaining solar observations which may be employed with the ordinary transit now commonly in use.

Another object of my invention is to provide a device of the type indicated which is very simple and inexpensive to make and which may be readily attached to or removed from the ordinary transit.

In its preferred form, my invention contemplates the provision of a device which is adapted to be attached to the ordinary surveyor's transit or other similar instrument. This device embodies a screen which is disposed a short distance 50 55

back of the eyepiece of the telescope. Between the screen and the eyepiece, I provide a shield which is so designed as to facilitate solar observations. The shield is made of opaque material but is provided with suitably arranged apertures for permitting a portion of the rays of the sun's image to pass beyond the shield and focus on the screen when the telescope is pointed at the sun. The shield is so designed that pointings can be taken directly on the center of the sun. The shield casts a symmetrical shadow on the screen which has at least three points uniformly disposed about the axis of the telescope with which the edge of the sun's image may be accurately registered by means of proper adjustment of the vertical and horizontal angles of the telescope. The result is the same as accurately sighting the intersection of the vertical and horizontal cross-wires on the center of the sun.

The preferred embodiment of my invention is illustrated in the accompanying drawings wherein similar characters of reference designate corresponding parts and wherein:

Figure 1 is a perspective view of an engineer's transit showing my solar observation attachment mounted thereon.

Figure 2 is a perspective view of the screen and cooperating solar shield.

Figure 3 is a view partly in side elevation and partly in section illustrating the complete attachment.

Figures 4, 5, 6 and 7 are plan views of the screen showing the shadow which will be cast thereon by the shield when the transit is directed at the sun, the different figures illustrating different positions of the sun's image.

Figure 8 is an enlarged plan view of the shield.

Figure 9 is an edge view of a portion of the shield showing the means for indicating whether or not the shield is perpendicular to the axis of the telescope of the transit, the shield being in this instance in proper perpendicular relationship.

Figure 10 is a similar view but showing the shield in a position where it is perpendicular to the axis of the telescope.

Figure 11 is a plan view of a screen which may be employed without using the shield.

Figure 12 is a combined perspective and diagrammatic view illustrating how solar observations may be made to determine the direction of a line.

Figure 13 is a table which should be used in conjunction with Figure 12 to illustrate an example of determining the direction of a line by solar observations made with my device.

With reference to the drawings, in Figure 1 I have illustrated an engineer's or surveyor's transit which may be of any ordinary form. It includes the telescope 2 which is fulcrumed, for movement in a vertical plane, as at 3. Suitable means is provided on the instrument for accurately adjusting the vertical and horizontal angles of the transit in the usual manner. My solar observation attachment is indicated generally by the numeral 4 in Figure 1.

As indicated best in Figures 1 and 3, my attachment includes a telescoping rod comprising a section 5 and a section 6. The section 5 receives the section 6. The hollow outer end of the section 5 is provided with a plurality of longitudinal slits 7. The end of the section 5 has its exterior surface threaded, as indicated at 8, and receives a cooperating threaded nut 9. Contacting inclined surfaces are provided at 10 on the end of member 5 and on the interior of the nut 9 and are so ar-

ranged that when the nut is rotated in a proper direction, the end of the member 5 will grip the section 6. Thus, a telescoping rod structure is provided which is of such a nature that the length thereof may be readily varied.

The end of the section 5 is provided with a clamping yoke 11 which is adapted to embrace and to be clamped upon one of the trunnion portions 12 which is formed as part of the telescope 2. This member 11 carries a stationary gripping member 13 and a movable gripping member 14 which have their inner sides so shaped as to fit the curved portion 12. The member 14 is carried on the outer end of a screw 15 which is free to rotate relative thereto. This screw is threaded through a portion of the member 11. Rotation of the screw by means of a knurled nut 16 will cause the member 14 to move towards and away from the member 13. In order to prevent rotation of member 14 relative to member 13, the member 14 is provided with a pin 17 which projects into and slides within a bore 18 provided in the member 11. Thus, with this structure the attachment may be clamped to or released from the portion 12.

The end of the section 6 of the telescoping rod 25 is attached to a small metal plate 19 by means of suitable lock nuts threaded on the end of member 6. The plate 19 is perpendicular to the rod. This plate 19 is connected by a compound hinge structure 23 to the solar shield 21 which I provide. The 30 compound hinge structure embodies a leaf 22 hinged to the inner edge of plate 19 at 23 and to the edge of a second leaf 24 as at 25. The opposite edge of the leaf 24 is hinged to one edge of the shield 21 as at 26. The shield 21 has secured thereto in spaced parallel relationship a screen 27, which is of greater area than the shield. The shield 21 and the screen 27 are attached to each other by means of the four pins 28. It will be noted that these pins extend from the screen 40 through the shield and project from the opposite side thereof as indicated at 29. These pins are perpendicular to the screen and the shield.

In positioning my attachment on the transit, it is clamped in such a position that the telescoping rod is in the same plane as the axis of the telescope of the transit. The shield 21 is so disposed that it is spaced behind the eyepiece 2a of the telescope a proper distance to obtain the desired size of the sun's image focused by the 50 telescope on the shield. The size of the image may be varied by changing the length of the telescoping rod. By means of the compound hinge structure 24, the shield 21 may be so positioned that the axis of the telescope 2 will pass through 55 the center thereof and the shield will be perpendicular to said axis. The projecting portions 29 of the pins 28 will indicate whether or not the shield 21 is perpendicular to the axis of the telescope when the telescope is pointed at the sun. 60 As indicated in Figure 9 when the shield is perpendicular to the axis, no shadow will be cast on the surface of the shield by each of the projecting portions 29 of the pins 28. However, as indicated in Figure 10, when the shield is not perpendicular 65 to the axis, a shadow will be cast on the surface of the shield by each of the projecting portions 29 of the pins 28.

The shield 21 may be made of metal or of any other suitable opaque material. The shape of 70 the shield is illustrated best in Figure 8. It has an X-shaped centrally disposed slot 30 formed therein, the arms 31 of which are disposed at right angles to each other. The outer end of each of the arms 31 of the slot is pointed as indicated at 75

32. On each of its edges a notch 33 is formed in the shield. These notches have side edges which are at right angles to each other and which converge at a point 34. Each point 34 is in alignment with a point 35 formed where the adjacent arms 31 of the slot converge. All of the points 32 and 34 are located on the same circle. As will appear later, the points 34 provide a plurality of points uniformly disposed about the axis of the telescope with which the edge of the image of the sun may be aligned in order to take a solar observation. All edges of the shield are beveled to form knife edges 36 to prevent blurring of the shadow cast by the shield on the screen 27. In using the transit with my attachment positioned thereon, as indicated, the transit is so disposed that the object end 2b points at the sun. The circular image 36a of the sun (Figure 2) will be focused on the top surface of the shield 21. The shadow 21a of the shield 21 will be cast on the screen 27, as indicated. The bright rays from the image of the sun will, under some conditions, pass through the X-shaped slot 30 and the notches 33 producing the respective configurations thereof on the screen in bright outline as indicated at 30a and 34a. The shadow 2c of the hair-lines of the instrument will also appear on the screen and will be in line with points 35a. When they are in line with points 35a, this will indicate that the center of the shield is at the axis of the telescope.

As previously indicated, in order to take a solar observation with my device it is desirable to align the edge of the image 36a of the sun with at least three of the points 34. In making solar observations with my device, it is merely necessary to adjust the telescope 2 of the instrument in a vertical and a horizontal plane until the edges of the sun's image 36a is located exactly at the points 34 on the shield which will be indicated when a very small point of light from the sun's image shows at the points 34a and no shadow shows at the points 32a, as indicated in Figure 5 which shows the shadow 21a of the shield on the screen. When the sun's image is located so that the results illustrated in Figure 5 are obtained, the observation can be taken. The shield is preferably positioned at such a distance from the eye piece of the telescope that the diameter of the sun's image will be slightly greater than the distance between the points 34a of opposite notches.

The solar observations may be quickly and easily made by first adjusting the telescope 2 in a vertical plane until the image 36a of the sun is at the proper vertical position on the screen, as indicated in Figure 4, but the image will be too far to the left to register with the points 34a which will be indicated by the shadows at the two points 32a to the right. Then, due to the movement of sun, the image will drift to the right from the position indicated in Figure 4 to the position indicated in Figure 5. At this instant, vertical and horizontal angle readings can be taken on the scales of the instrument. The sun's image will continue to drift to the right out of coincidence with the points 34a, as indicated in Figure 6. In Figure 7 the conditions are shown such as will be encountered when the sun's image is not in the correct vertical position which will be indicated by the shadows at the two lower points 32a.

Thus, with my device at least three points are provided which are uniformly spaced about the axis of the telescope and with which the edge of the image of the sun may be aligned and at

that instant the necessary readings may be taken on the transit. It will be a very simple matter to bring the instrument into proper adjustment where the edge of the image will align with the proper points.

It is not absolutely necessary to employ the screen 27. The screen may be dispensed with and the shield 21 only may be used. In using the shield only, the image of the sun can be brought into alignment with the points 34 on the shield. The image will be bright enough to show on the shield itself.

In Figure 11 I illustrate a shield which may be used without a screen. In this instance the shield has a main portion 21b of a suitable color and portions 33b and 30b, corresponding to the notches 33 and slot 30 of the shield 21, which are of a different color. With this structure the image of the sun should be brought into alignment with the points 34b. This shield will be used substantially as the shield 21.

In using my device to determine the direction of a line, for example line (AB) of Figure 12, which might be a bridge, the instrument is set at the point (A). Then the engineer or surveyor 25 cites across the bridge to the opposite side to the point (B). The vernier of the horizontal circle on the transit has been set at O and the lower motion of the transit is clamped. My attachment is then positioned properly on the transit 30 and solar observations are taken in the manner illustrated in Figure 12. These observations are taken by pointing telescope 2 at the sun and aligning the sun's image with at least three of the points 34 of the shield 21, as previously 35 explained. As indicated in Figure 12, and in the table in Figure 13, ten of these pointings are taken. Five are taken with the transit in one position and five taken with the transit in a reverse position in the usual manner in order to 40 avoid errors due to inadjustments in the transit. Each time an observation is taken, the horizontal and the vertical angles are read on the instrument and are recorded in the table as indicated. It will be noted that in the table there is provided 45 columns for the time, the rate of horizontal movement of the sun, the horizontal circle, the rate of vertical movement, and the vertical circle. It will also be noted from the table that the speed of the horizontal and vertical movement of the sun can be determined before and 50 after the observations. The speed of movement of the sun in a horizontal direction may be determined in the manner illustrated diagrammatically in the table. To do this it is merely necessary to have the sun's image tangent with the vertical cross hair 2c on the screen 27 and allow the sun's image to move into a position where the opposite edge of the image is in alignment with the points 34. In other words, the sun is 55 permitted to move through its semi-diameter and the time this takes is noted. The vertical speed can be determined in a similar manner.

The average of the vertical angle is then used in the reduction formula illustrated in the table 65 to determine the azimuth of the sun which will be the imaginary line (AC). The average of the horizontal component found by the observations is then subtracted from the azimuth of the sun which will give the azimuth of the line (AB). 70

It is apparent from the above description that I provided a device for obtaining solar observations by which the observations may be obtained in a highly accurate and quick manner. My device is such that the method of taking solar ob- 75

servations is greatly simplified as compared to the ordinary methods of making solar observations. The pointings are taken directly and accurately on the center of the sun. The shield which I provide for use with a screen is of such a nature that it blanks out most of the sun's bright image thereby obtaining the proper contrast of light. It accentuates the three or more points of light which are used in the pointings on the sun. It requires much less time in taking the pointings than with the ordinary methods and assures more accurate pointings. It provides a means to accurately measure the speed of the sun both horizontally and vertically. It gives actual progressive recordings of horizontal and vertical angles so that these angles can be checked by the rate of travel of the sun.

Many other advantages will be apparent from the preceding description, the drawings and the following claims.

By the term "transit" in the following claims I also intend to cover a theodolite or other similar instrument.

Having thus described my invention, what I claim is:

1. An attachment for an engineer's transit comprising a shield member, means for supporting said member on the transit for movement with the telescope thereof, said member being spaced from the eye piece of the telescope along the optical axis thereof and being disposed substantially perpendicular to said axis, said member having at least three observable points thereon disposed along a circle which normally has its center at said axis and with which the periphery of the sun's image may be brought into registry when the telescope is pointed at the sun by adjustment of the angular position of the telescope.

2. An attachment for an engineer's transit comprising a shield, means for supporting said shield on the transit for movement with the telescope thereof, said shield being spaced from the eye piece of the telescope along the optical axis thereof and being disposed substantially perpendicular to said axis, a screen attached to the shield and disposed substantially parallel thereto at a point spaced farther from said eye piece, said shield having openings therein so arranged that a shadow with at least three observable points disposed along a circle which normally has its center at said axis is formed on the screen with which the periphery of the sun's image may be brought into registry when the telescope is pointed at the sun by adjustment of the angular position of the telescope.

3. An attachment for an engineer's transit comprising a shield member, means for supporting said member on the transit for movement with the telescope thereof, said member having a flat surface spaced from the eye piece of the telescope along the optical axis thereof and being adapted to be disposed substantially perpendicular to said axis, said member being so mounted that it may be adjusted axially of the telescope and transversely thereof, said member having at least three observable points thereon disposed along a circle which normally has its center at said axis and with which the periphery of the sun's image may be brought into registry when the telescope is pointed at the sun by adjustment of the angular position of the telescope.

4. An attachment for an engineer's transit comprising a shield, means for supporting said shield on the transit for movement with the

telescope thereof, said shield being spaced from the eye piece of the telescope along the optical axis thereof and being disposed substantially perpendicular to said axis, said shield being opaque but having notches cut into the periphery thereof, said shield also having slots formed therein, the vertices of the notches and the pointed ends of the alternating slots all being equally spaced on the same circle with a center normally lying in the axis of the telescope and in such a manner that the periphery of the sun's image may be brought into registry with such points when the telescope is pointed at the sun by adjustment of the angular position of the telescope.

5. An attachment for an engineer's transit comprising a shield, means for supporting said shield on the transit for movement with the telescope thereof, said shield being spaced from the eye piece of the telescope along the optical axis thereof and being disposed substantially perpendicular to said axis, said shield being opaque and being substantially square, said shield having V-shaped notches cut into the side edges thereof, said shield also having an X-shaped slot cut therein, the ends of said slot being V-shaped, the vertices of the notches and the vertices of the ends of the slots all being equally spaced on the same circle with a center normally lying in the axis of the telescope in such a manner that the periphery of the sun's image may be brought into registry with such points when the telescope is pointed at the sun by adjustment of the angular position of the telescope.

6. An attachment for an engineer's transit comprising a shield, means for supporting said shield on the transit for movement with the telescope thereof, said shield being spaced from the eye piece of the telescope along the optical axis thereof and being disposed substantially perpendicular to said axis, said shield being opaque and being substantially square, said shield having V-shaped notches cut into the side edges thereof, said shield having an X-shaped slot cut therein, the ends of said slot being V-shaped, the vertices of the notches and the vertices of the ends of the slots all being equally spaced on the same circle with a center normally lying in the axis of the telescope in such a manner that the periphery of the sun's image may be brought into registry with such points when the telescope is pointed at the sun by adjustment of the angular position of the telescope, and a screen attached to the shield and disposed substantially parallel thereto so that a shadow produced by the screen will appear thereon.

7. An attachment for an engineer's transit comprising a shield, means for supporting said shield on the transit for movement with the telescope thereof, said shield being spaced from the eye piece of the telescope along the optical axis thereof, said shield being mounted on the transit in such a manner that it may be angularly adjusted relative to said axis, said shield having at least three observable points thereon disposed along a circle which normally has its center at said axis and with which the periphery of the sun's image may be brought into registry when the telescope is pointed at the sun, said shield having pins disposed perpendicular to the surface thereof disposed towards the eye piece of the telescope to indicate whether or not said shield is perpendicular to the axis of the telescope.

8. An attachment for an engineer's transit comprising a shield having observable points thereon with which the sun's image is adapted

5 to register when the transit is pointed at the sun, said shield being carried on the lower end of a rod which is attached to the horizontal axis of the telescope and is disposed in the same plane as the longitudinal axis of the telescope so that the shield will be along the optical axis of the telescope, said rod having its length adjustable to properly position the shield longitudinally of

the telescope in spaced relationship to the eyepiece thereof, and a compound hinge structure for connecting said shield to the rod which permits adjustment of the shield transversely of the longitudinal axis and angularly relative to said axis. 5

CLAUDE H. WALL.
